UNITED STATES PATENT OFFICE

JOHN P. CAVANO AND GEORGE VONDICAKIS, OF CLEVELAND, OHIO

SERVING AND WASHING TRAY

Application filed May 24, 1930. Serial No. 455,201.

This invention relates to a serving and washing tray or rack adapted especially for use in serving, dish-washing, storage and shipment of cups, such as tea cups or bouillon 5 cups.

An object of the invention is to provide a device of this character which shall be cheap and simple in construction and efficient in use, which will provide for stacking of a plurality 10 of the trays irrespective of whether the cover is in place, which will allow of comparatively rough handling without danger of breaking the cups, and which will admit of the transportation or storage of a plurality of cups 15 having either one handle or two diametrically opposed handles. With the foregoing and other objects in view, the invention consists in the details of construction and arrangement of parts hereinafter described and 20 claimed.

Fig. 1 is a top plan view of my improved serving and washing tray showing the cover in position; Fig. 2 is a side elevation thereof; Fig. 3 is a transverse section; Fig. 4 is a fragmentary detail view designed to show clearly 25 the construction of the cover; and Fig. 5 is a fragmentary bottom plan view showing one feature of the stacking arrangement.

The essential framework consists of a plurality 30 of corner angle irons. The angle irons 10 extend along the long sides at the bottom and are joined by the angles 11 extending across the ends at the lower portion. Four upstanding angles 12 are rigidly connected 35 with the angles 10 and 11 at the ends thereof and thus provide a skeleton of the framework. The side and end walls of the tray consist of zigzag bars 13 extending the length and breadth of the tray respectively and each 40 having a horizontal portion 13^a near the corner, and each being joined at each end with one of the corner angle irons 12 at the top thereof. Extending across the bottom of the tray by way of a bottom wall are a plurality 45 of rods 14 each being secured at or near an end to one of the angle irons 10.

Soldered, welded or otherwise secured to the bars 14, which are arranged in pairs, are a plurality of rows of cup sockets secured, 50 one row to each pair of rods 14. Each cup

socket comprises a base portion provided with an annularly upwardly extending flange 16 and a pair of wire members 17 and 18 defining a cup-shaped socket, being spaced apart at their ends to allow the handles of a cup to project between them, and provided with one or more braces 19, as may be required to impart sufficient rigidity.

The cover consists of a rectangular frame made up of side members 20 and end members 21 together with longitudinally extending metallic bars 22, transversely extending non-metallic bars 23, and a latching means consisting of hooks 24 and spring latch members 25 adapted to engage over the horizontal portions 13^a of the zigzag bars 13. The bars 23 may be of wood and secured under struck-out curved tongues 26. It will be evident from the drawings that the wooden bars 23 extend directly above each row of cup sockets to afford protection to the cups contained therein. It is obvious that the number of bars 22 and 23 may be varied as desired to provide for suitable rigidity and cushioning effect.

An important feature of my invention is the ability to stack a plurality of these devices one above the other either with the cover on or without it, for serving, shipping or other purposes. It will be observed that the cover is shorter than the tray and that the corners of the tray are thereby exposed, there being a considerable distance between the end edges of the corner angle irons 12 and the adjacent bars 21. On the bottom of the tray at each corner thereof are provided downwardly extending projections 28 which may engage within the corners of a similar tray when placed thereupon. It is obvious that these projections 28 may be of such length as to engage the corners of an underlying tray irrespective of whether the cover is in position, or they may be of a length to engage only when the cover is removed.

From the foregoing, it will be obvious that I have provided a simple construction well adapted for its intended use, and while I have illustrated the preferred embodiment, I wish it understood that I am not limited to the details thereof but that I may carry

out my invention in numerous forms within the scope of the appended claims.

Having thus described my invention, what we claim is:

- 5 1. A serving and washing tray comprising a skeleton tray made up of a plurality of angle irons one for each corner, and making up a tray structure, a plurality of pairs of cross bars forming a bottom, a plurality of cup sockets attached to each pair of bars, each cup socket comprising a wire skeleton framework defining curved socket walls with diametrically opposed slots and a flanged sheet metal bottom, side walls, each comprising a zigzag wire, and a cover comprising a metallic frame shorter than said tray and provided with hooks at one side to engage a portion of a side wall, a spring latch at the other side to engage the opposite side wall, 20 and non-metallic cross members carried by said cover above said cup sockets to prevent breakage.
2. A serving and washing tray comprising a skeleton tray made up of a plurality of angle irons one for each corner, and making up a tray structure, a plurality of pairs of cross bars forming a bottom, a plurality of cup sockets attached to each pair of bars, each cup socket comprising a wire skeleton framework defining curved socket walls with diametrically opposed slots and a flanged sheet metal bottom, side walls, each comprising a zigzag wire, and a cover comprising a metallic frame shorter than said tray and provided with hooks at one side to engage a portion of a side wall, a spring latch at the other side to engage the opposite side wall, and non-metallic cross members carried by said cover above said cup sockets to 35 prevent breakage, there being a projection on the bottom of said tray at each corner thereof adapted to engage in the exposed upper corners of a similar tray.

In testimony whereof, we hereunto affix our signatures.

JOHN P. CAVANO.
GEORGE VONDICAKIS.
